CLAIM

The ornamental design for a projector lamp, as shown and described.

DESCRIPTION

FIG. 1 is a perspective view of a projector lamp design showing my new design.

FIG. 2 is a bottom side perspective view of a projector lamp.

FIG. 3 is a front view of a projector lamp.

FIG. 4 is a rear view of a projector lamp.

FIG. 5 is a left side view of a projector lamp.

FIG. 6 is a right side view of a projector lamp.

FIG. 7 is a top view of a projector lamp.

FIG. 8 is a bottom view of a projector lamp; and,

FIG. 9 is an enlarged detail view of area 9 shown in FIG. 3. The broken lines in the figures illustrate portions of the projector lamp. The broken-line circle and lead line in FIGS. 3 and 9, which illustrate the boundary of the enlarged view, represents a detail call-out. The broken lines form no part of the claimed design.
